Des. 236,846
Patented Sept. 16, 1975

236,846

STROBOSCOPIC LIGHT UNIT HOUSING FOR AIRCRAFT

Cecil P. Bishop, 1401 Nob Hill Road,
San Marcos, Calif. 92069

Filed May 13, 1974, Ser. No. 469,118

Term of patent 14 years

Int. Cl. D26—06

U.S. Cl. D48—32 R

FIG. 1 is a perspective view of a stroboscopic light unit housing for aircraft, showing my new design.

FIG. 2 is an end elevational view as taken from the right hand end of FIG. 1.

FIG. 3 is a side elevational view as taken from the right hand side of FIG. 2.

FIG. 4 is a top plan view thereof.

FIG. 5 is a bottom plan view thereof.

I claim:

The ornamental design for a stroboscopic light unit housing for aircraft, substantially as shown.
